FLYING BOAT AND HELICOPTER COMBINATION

Igor B. Bensen, Raleigh, N.C., assignor to Bensen Aircraft Corporation, Raleigh, N.C., a corporation of North Carolina

Application January 22, 1957, Serial No. 44,555

Term of patent 14 years

(Cl. D71—1)

Des. 187,507

PAGE 2

FIG. 3

FIG. 4

FIG. 5

Figure 1 is a perspective view of a boat and helicopter combination embodying my design;

Figure 2 is a side elevational view thereof;

Figure 3 is a front elevational view thereof;

Figure 4 is a rear elevational view thereof; and

Figure 5 is an enlarged partial section along line 5—5 of Figure 2.

The rotor blade has been omitted from Figures 2, 3 and 4 for convenience of illustration only.

What is claimed is:

The ornamental design for a boat and helicopter combination, as shown.
